COMBINED FOOD PACKAGING AND DISPLAYING TRAY

Hugh R. Weiss, Montclair, N.J., assignor to The Pantasote Company of New York, Inc., New York, N.Y., a corporation of New York

Filed June 3, 1968, Ser. No. 12,186

Term of patent 14 years

Int. Cl. D9—04

U.S. Cl. D9—187

FIG. 1

FIG. 2

FIG. 3

FIG. 4

FIG. 2 is a top plan view thereof;

FIG. 3 is an end view taken on lines 3—3 of FIG. 2;

FIG. 4 is an enlarged fragmentary plan view of the left partition thereof of FIG. 1;

FIG. 5 is an enlarged section taken on line 5—5 of FIG. 2; and

FIG. 6 is an enlarged section taken on line 6—6 of FIG. 2.

I claim:

The ornamental design for a combined food packaging and displaying tray, as shown and described.
